DE WATT PEPPER, OF NEW MILFORD, CONNECTICUT.

DESIGN FOR A COUCH-FRAME.

SPECIFICATION forming part of Design No. 36,206, dated January 27, 1903.

Application filed December 26, 1902. Serial No. 136,746. Term of patent 3½ years.

To all whom it may concern:

Be it known that I, DE WATT PEPPER, a citizen of the United States, residing at New Milford, in the county of Litchfield and State of Connecticut, have invented and produced a new, original, and ornamental Design for a Couch-Frame; and I do hereby declare the following to be a full, clear, and exact description of the invention, such as will enable others skilled in the art to which it appertains to make and use the same.

The accompanying drawing shows a front elevation of my new design.

As shown in the drawing, the leading or material features of my design consist of the sides 1 of the frame, having a general scroll-like appearance and bounded by compound curves which gradually diverge from top to bottom, the seat-frame, whose front middle portion 2 is horizontally disposed, the portions 3 of said seat-frame beyond the portion

2 being curved upwardly and bounded by convexo-concave curves, said portions 3 at their lateral extremities terminating in upwardly-extending knob-like portions 4, and the feet 5, upon which the portions 3 rest, said feet having generally scroll-like ornaments 7 at the top immediately below the portions 3, while said feet themselves terminate in toe-like representations 6. 30

Having thus described my invention, what I claim as new, and desire to secure by Letters Patent, is—

The ornamental design for a couch-frame, as herein shown and described. 35

In testimony whereof I affix my signature in presence of two witnesses.

DE WATT PEPPER.
